CLAIM

The ornamental design for a door, as shown and described.

DESCRIPTION

FIG. 1 is a front perspective view of a first version of the door;

FIG. 2 is a front elevational view thereof;

FIG. 3 is a rear elevational view thereof;

FIG. 4 is an enlarged view of a portion of the door shown in the encircled portion “4” of FIG. 1;

FIG. 5 is a top plan view thereof;

FIG. 6 is a bottom plan view thereof;

FIG. 7 is a cross sectional view taken along line 7-7 of FIG. 2;

FIG. 8 is a cross sectional view taken along line 8-8 of FIG. 2;

FIG. 9 is an enlarged view of a portion of the door shown in the encircled portion “9” of FIG. 7;

FIG. 10 is an enlarged view of a portion of the door shown in the encircled portion “10” of FIG. 8;

FIG. 11 is a right side elevational view thereof;

FIG. 12 is a left elevational view thereof;

FIG. 13 is a cross sectional view taken along line 13-13 of FIG. 2;

FIG. 14 is an enlarged view of a portion of the door shown in the encircled portion “14” of FIG. 13;

FIG. 15 is an enlarged view of a portion of the door shown in the encircled portion “15” of FIG. 13;

FIG. 16 is a front perspective view of a second version of the door;

FIG. 17 is a front elevational view thereof;

FIG. 18 is a rear elevational view thereof;

(Continued)

FIG. 19 is an enlarged view of a portion of the door shown in the encircled portion “19” of FIG. 16;
 FIG. 20 is a top plan view thereof;
 FIG. 21 is a bottom plan view thereof;
 FIG. 22 is a cross-sectional view taken along line 22-22 in FIG. 17;
 FIG. 23 is a cross-sectional view taken along line 23-23 in FIG. 17;
 FIG. 24 is an enlarged view of a portion of the door shown in the encircled portion “24” of FIG. 22;
 FIG. 25 is enlarged view of a portion of the door shown in the encircled portion “25” of FIG. 22;
 FIG. 26 is a right side elevational view thereof;
 FIG. 27 is a left elevational view thereof;
 FIG. 28 is a cross sectional view taken along line 28-28 of FIG. 17;
 FIG. 29 is an enlarged view of a portion of the door shown in the encircled portion “29” of FIG. 28; and,
 FIG. 30 is an enlarged view of a portion of the door shown in the encircled portion “30” of FIG. 28.
 The dash-dash or evenly broken lines depict portions of the door that form no part of the claimed design. The dot-dot-dash broken lines depict the limits of the enlarged views and form no part of the claimed design.
 Portions of the drawings shown in dashed lines form no part of the claimed design.
